ELECTRICAL SWITCH

John D. Crecca, United States Navy

Application April 9, 1942, Serial No. 438,285

10 Claims. (Cl. 200—83)

(Granted under the act of March 3, 1883, as amended April 30, 1928; 370 O. G. 757)

My invention relates to electrical switches, and in particular to the type of switch which is constructed for use under water for controlling electrical apparatus such as, for example, electric welding guns.

This application is a continuation-in-part of my application, Serial No. 362,714, filed October 23, 1940, for "Subaqueous end wending device."

A general object of my invention is to provide an improved electrical switch which is suitable for manual operation under water.

Another object is to provide a switch adapted for under-water operation in which the force of the water acting upon the switch contact operating member and tending to close the switch contact is counteracted by an opposing force set up in an opposite direction.

Another object of my invention is to provide a switch which can be adjusted to compensate for water pressure acting upon the switch operating member so that the switch may be useful at various depths of water.

Another object is to provide a switch in which the operating member thereof can be actuated with substantially the same manually applied force irrespective of the distance which the switch may be located below the surface of the water.

A further object of my invention is to provide a switch adapted for under-water operation which can be controlled automatically and remotely by applying a pressure from an auxiliary source of fluid supply to the switch contact operating member in such manner as to oppose the pressure of the water acting upon such member. The applied pressure is so regulated that when the force created thereby is greater than the force of the water acting upon the contact operating member, the switch contacts will be maintained open, but when such force is less than that due to the water pressure, the operating member will yield to the force of the water and close the switch contacts.

A still further object is to provide an under-water switch which is so calibrated that the operator can quickly and accurately adjust the pressure compensation mechanism to balance the water pressure acting upon the switch operating member at the depth of water at which he may be working.

These and other objects of my invention will become more apparent from the following detailed description, and from the accompanying drawing, in which:

Fig. 1 is a side view, partly in section, of a switch embodying my invention;

Fig. 2 is a sectional side view of a modified form of switch;

Fig. 3 is a view taken on lines 3—3 of Fig. 2a; and

Fig. 4 is a sectional side view of another modification of a switch embodying my invention.

Referring now to Fig. 1, my improved switch apparatus comprises a casing 1 which may be of any waterproof, electrically insulating material such as fibre, within which is carried the switch contacts. If desired, these contacts may be completely assembled in a separate casing 7 from which a plunger 8 extends, the latter being operable when depressed to close the switch contacts. A suitable contact assembly is shown in U. S. Patent No. 1,960,020.

The housing 1 may be secured in position by inserting it between the side walls of a U-shaped clamping member 6 and securing it in such position by means of screws 9.

Ears are provided on the U member 6 and these rest upon an internally shouldered portion of the casing 1. The U member 6 may be secured to the casing 1 by means of screws, which pass through apertures in the ear portions of the member and thread into the casing.

Resting upon the top of the U member 6 is a resilient body member 5 which may be made of cellular rubber or any other suitable material.

30 A flexible diaphragm 2, which may also be made of rubber, is placed over the resilient member 5 and is secured to the casing by means of a rigid plate member 3 which may be made of metal, if desired. This plate member 3 includes an apertured portion within which a switch button 4 is located. A stud portion of switch button 4 passes through an opening in the flexible diaphragm 2 and is secured tightly within such opening by a nut and washer. When button 4 is depressed the studded portion thereof presses upon and moves the plunger 8 which operates to close the contacts within the housing 7.

Leads 10 from the switch contacts may be carried out of the casing through a stuffing box 11.

45 When the switch is immersed in water, the pressure of the water (which increases with depth at the rate of approximately 62.5 lbs. per sq. ft. for each foot of depth) acting upon the exposed area of the flexible diaphragm 2 will tend to move the diaphragm 2 and button 4 towards the plunger 8. Such movement is opposed, however, by the restoring force set up within the resilient body member 5 as the latter is compressed, which prevents untimely actuation of plunger 8 by the button 4, thereby pre-

venting the switch contacts from being moved to a closed position.

Cellular rubber may be obtained in varying degrees of resiliency. Hence the particular type utilized for member 5 will be so chosen that for a given pressure of water (which will be determined by the distance below the surface of the water that the apparatus on which the switch is installed is intended to operate), it will prevent the button 4 from traveling a distance sufficient to abut the plunger 8. The additional force necessary to cause the button 4 to abut and depress plunger 8 can then be supplied manually.

In Figs. 2 and 3, I have illustrated a modified form of switch which is adapted to operate at depths greater than those at which a switch made in accordance with Fig. 1 can operate. The switch has a casing 12 which may be of the same material as the casing 1. In this particular embodiment, the casing 12 is rectangular but it is obvious that it may be of any suitable shape. Within the casing 12 is a rigid metallic support member 21 which has a central aperture cut therein and rests upon an internally shouldered portion of the casing and secured thereto by suitable screws.

A resilient body member 17 which is non-porous, such as cellular rubber, is provided with a central apertured portion and rests upon the support 21. Member 17 is fixed in position by a non-porous diaphragm 13 of flexible material such as rubber which is clamped at its periphery between a pair of rigid members 14 and 16. These latter members, with the flexible diaphragm 13 therebetween are secured to the casing 12 by a bolt and nut at each corner thereof.

A manually operable button 15 extends through a central opening in diaphragm 13 and is secured thereto by a nut 18 which threads on the shank portion 15' of button 15.

A T-shaped contactor 20 having a stem 20' is similarly secured through the apertured portion of a second flexible diaphragm 22 by nut 19.

A pair of switch contacts 23-23 are fastened in position to inwardly projecting tongue portions 29 in the casing 12 by means of screws. Leads 25-25 soldered to lugs 24-24 are taken out through a stuffing box 26.

It will be noted that the outer periphery of resilient member 17 is spaced from the internal wall of casing 12, thus leaving a chamber 17' which extends around the casing. This chamber connects with the exterior of the casing 12 through a pipe 28 which threads into a threaded opening 27 in the casing 12. To prevent seepage of water or other fluid from the chamber 17' to the central opening in the resilient member 17, the top and bottom surfaces of the latter may be glued respectively to the diaphragm 13 and disc 21.

If the pipe 28 is sealed, operation of the switch is similar to that in Fig. 1. The switch would be utilized in this manner when the water pressure acting upon the water exposed surface of the diaphragm was not too great.

For operation at greater depths, the pipe 28 may be left open, in which case the chamber 17' will be filled with water as the switch is carried below the water's surface. The pressure of the water in chamber 17' will then be the same as that acting upon the exterior surfaces of the casing. This pressure is exerted transversely against the side walls of the resilient member 17, causing them to be depressed inwardly which thereby serves to "stiffen" the resilient member 75

and to thus increase the opposing force which this member presents to resist depression of the flexible diaphragm by the force of the water acting downwardly thereon.

If the pressure in chamber 17' does not sufficiently offset the pressure of the fluid acting downwardly on diaphragm 13, the pipe 28 may be connected to a separate source of fluid supply (not shown), and fluid pumped into the chamber at the desired pressure. This fluid may be liquid or gas, such as compressed air.

Manual operation is similar to that in Fig. 1.

This type of construction permits the switch contacts 23-23 to also be operated automatically, if desired, instead of manually.

To effect automatic operation, fluid would be pumped into chamber 17' until the total force acting upwardly against the under side of the diaphragm 13 is greater than the total force exerted downwardly on the upper side of the diaphragm 13 by the water. This excess of force on the under side of the diaphragm would be just sufficient to keep the shank portion 15' of button 15 out of engagement with the stem 20'. When it is desired to close the switch, a valve in the fluid supply line would be opened, whereupon the pressure due to the fluid in chamber 17' would be released. Since the total force of the water acting downwardly upon the diaphragm would then be greater than the opposing force set up on the under side of the diaphragm, the diaphragm would then move downwardly, causing button shank 15' to engage the stem 20' of contactor 20 and move the latter until it bridges and closes a circuit through contacts 23-23.

To open the circuit, fluid would again be pumped into chamber 17' until the pressure was sufficient to cause contactor 20 to move upwardly and break its engagement with contacts 23-23.

In Fig. 4 I have provided another type of construction whereby the force of the water acting downwardly against the upper side of the flexible diaphragm may be balanced at any depth by a counterforce acting upwardly against the under side of said diaphragm.

In this modification the switch comprises a base plate 40 upon which a cylindrical casing 30 is mounted for rotation. A plurality of graphite plugs 41 are provided in order that the casing may rotate easily upon the base plate 40, and a stuffing box 38 together with a gland 39 prevents water from entering the interior of the switch as the casing 30 is rotated.

An annular disc member 36 is provided with threads at the periphery thereof and these threads engage with complementary threads 48 which are provided on the inside wall of the casing 30.

One or more guide members 37, which are fixedly secured to the base plate 40, extend upwardly through aligned openings 49 provided in the disc 36 and function to prevent the disc 36 from rotating with the casing 30 as the latter is turned on base plate 40.

Since disc 36 cannot rotate, the interaction between the threads will cause it to move in translation upwardly or downwardly, depending upon the direction in which the casing 30 is rotated.

The top of the casing 30 is closed by a flexible diaphragm member 31 and, if desired, an annular shaped rigid member 33 may also be provided to assist in clamping the diaphragm 31 to the casing 30 to make it watertight. A coiled

spring member 34 is seated upon an upturned portion of the disc 36 and is secured in position between the disc 36 and flexible diaphragm 31.

A contactor 35 is secured to diaphragm 31 by nut 32 which serves as a manually operable switch button. Contactor 35 extends downwardly into the body of the switch and terminates in an L which is provided to bridge a pair of circular switch contact members 42 and 43 which are supported, respectively, on cylindrical posts 46 and 47. Leads 44-44 may be respectively connected to each contact member and are carried to the outside of the switch through a stuffing box 45 which may be provided in base plate 40.

This type of switch operates in the following manner: When the switch is taken below the surface of the water, it is evident that a force due to the pressure head of the water will act upon the flexible diaphragm 31 and tend to depress it. This force can be counteracted, however, by turning the cylindrical casing 30 on the base plate 40 in such a direction as to cause the disc 36 to move upwardly and compress the coiled spring 34. The restoring force which is thus built up in the coiled spring, due to its compression, will act upwardly against the under side of the flexible diaphragm 31 and balance out the force of the water on the opposite side of the diaphragm.

I have also provided indicator means whereby the operator of the switch may adjust the compression on the coiled spring 34 below the surface of the water to suit the particular depth at which he is working. Such means comprise a plurality of lugs 51 which are spaced around the periphery of the base plate 40, and an indicator arm 50 which is attached to and rotates with the casing 30. Consecutive lugs 51 may be marked with depth settings in any suitable intervals, such as, for example, 25 ft., 50 ft., 75 ft., etc. If unable to see the indicia on the lugs, the operator, knowing the characteristics of the indicator, can easily set the arm 50 opposite the proper lug 51 by tactile sense.

In conclusion, while I have shown and described certain embodiments of my invention, it will be apparent that changes and modifications may be made therein without departing from the spirit and scope of my invention, as defined in the appended claims.

For example, in some instances it may be desirable to replace the cellular rubber member in Fig. 1 with a spring member such as member 34, shown in Fig. 4. Also, in some cases, it may be desirable to insert a rigid disc member between the top of the coil spring 34 and the flexible diaphragm 31 in order to better distribute the opposing force set up by the spring over the entire surface of the diaphragm.

As another example, it may be desired to substitute a coil spring such as member 34 shown in Fig. 4 to replace resilient member 17 in Fig. 2. In such case disc 21 is secured to causing 12 by a water-tight connection and second flexible diaphragm 22 is made up with a water-tight joint to disc 21.

Also, while I have described my invention in connection with its use as an under-water switch, it will be evident that it may be used equally as well in other fluid mediums such as compressed air.

The invention described herein may be manufactured and used by or for the Government of

the United States of America for governmental purposes without the payment of any royalties thereon or therefor.

Having fully described my invention, I claim:

- 5 1. In a switch adapted for use under fluid pressure such as in under-water operation, the combination comprising a switch casing, switch contact means, means for supporting said contact means within said casing, a flexible diaphragm closure member for said casing, means operable upon a depression of said closure member to actuate said contact means, a support and a resilient pad member disposed between the underside of said diaphragm closure member and said support, said resilient member being adapted to be distorted upon depression of said closure member whereby the restoring force created therein will be exerted outwardly against said closure member to oppose fluid pressure acting thereupon in an opposite direction.
- 10 2. In a switch adapted for use under fluid pressure such as in under-water operation, the combination comprising a switch casing, a pair of stationary switch contact members, means for supporting said contact members in spaced relation within said casing, a flexible diaphragm closure member for said casing, a movable switch member operable upon a depression of said closure member to bridge said stationary contact members to close a circuit therethrough, a support plate, and a resilient pad member disposed between said support plate and the underside of said diaphragm closure member, said resilient member being adapted to be compressed upon depression of said closure member whereby the restoring force created therein will be exerted outwardly against said closure member to oppose fluid pressure acting thereupon in an opposite direction.
- 15 3. A switch adapted for use under fluid pressure such as in under-water operation comprising a casing, switch contact means disposed therein, a flexible diaphragm closure member for said casing, means operable upon depression of said diaphragm member to actuate said contact means, and means for admitting fluid under pressure to the interior of said casing to oppose fluid pressure acting upon the exterior of said diaphragm member.
- 20 4. In a switch adapted for use under fluid pressure such as in under-water operation, the combination comprising a switch casing, a flexible diaphragm closure member for said casing, a support plate, a non-porous resilient member disposed between said support plate and the underside of said closure member, said resilient member being spaced from the inner wall of said casing to form a chamber therebetween, means for admitting fluid under pressure to said chamber, switch contact means, and means operable upon a depression of said flexible diaphragm member to actuate said contact means.
- 25 5. In a switch adapted for use under fluid pressure such as in under-water operation, the combination comprising a base plate, a cylindrical casing, the inner wall of which is threaded, means for supporting said casing on said base plate for rotation thereon, a disc member, the periphery of which is threaded for threaded engagement with the threaded inner wall of said casing, an upstanding guide member secured to said base plate, said guide member being extended through an aligned opening in said disc whereby rotation of said casing upon said base plate will produce translatory motion of said disc, a flexible dia-

phragm, means securing said diaphragm to said cylindrical casing to close the latter, a resilient member, said resilient member being supported between said diaphragm and said disc so that as said resilient member is compressed by translatory motion of said disc the restoring force created therein will oppose fluid pressure acting upon said diaphragm, switch contact means, and means operable upon depression of said flexible diaphragm to actuate said contact means.

6. The combination in claim 5 and including indicator means associated with said casing whereby its position may be set to apply on said resilient member the amount of compression necessary to balance the fluid pressure acting upon said flexible diaphragm.

7. In a switch adapted for use under fluid pressure such as in under-water operation, the combination comprising a base plate, a cylindrical casing, the inner wall of which is threaded, means for supporting said casing on said base plate for rotation thereon, a disc, the periphery of which is threaded for threaded engagement with the threaded inner wall of said casing, an upstanding guide member secured to said base plate, said guide member being extended through an aligned opening in said disc whereby rotation of said casing upon said base plate will produce translatory motion of said disc, a flexible diaphragm, means securing said diaphragm to said cylindrical casing to close the latter, a spring, said spring being supported between said diaphragm and said disc so that as said spring is distorted by translatory motion of said disc the restoring force created therein will oppose fluid pressure acting upon said diaphragm, switch contact means, and means operable upon depression of said flexible diaphragm to actuate said contact means.

8. The combination in claim 7 and including indicator means associated with said casing whereby its position may be set to apply to said spring member the amount of distortion necessary to balance the fluid pressure acting upon said flexible diaphragm.

9. In a switch adapted for use under fluid pres-

sure such as in under-water operation, the combination comprising a base plate, a cylindrical casing, the inner wall of which is threaded, means for supporting said casing on said base plate for rotation thereon, an annular disc, the periphery of which is threaded for threaded engagement with the threaded inner wall of said casing, an upstanding guide member secured to said base plate, said guide member being extended through an aligned opening in said disc whereby rotation of said casing upon said base plate will produce translatory motion of said disc, a flexible diaphragm, means securing said diaphragm to said casing to close the latter, a coiled spring member, said spring being supported between said diaphragm and said disc so that as said spring is compressed by translatory motion of said disc the restoring force created therein will oppose fluid pressure acting upon said diaphragm, a pair of circular switch contact members, means for mounting said contact members concentrically on said base plate, and means operable upon depression of said diaphragm to bridge said contact members.

10. In a switch adapted for use under fluid pressure such as in under-water operation, the combination comprising a base plate, a cylindrical casing, means for supporting said casing on said base plate for rotation thereon, a disc member disposed within said casing, means operable upon rotation of said casing to effect translatory motion of said disc member, a flexible diaphragm, means securing said diaphragm to said casing to close the latter, a resilient member, said resilient member being supported between the under side of said diaphragm and the upper side of said disc member so that as said resilient member is compressed by translatory motion of said disc member the restoring force created therein will oppose fluid pressure acting upon said diaphragm, switch contact means, and means operable upon depression of said flexible diaphragm to actuate said contact means.

JOHN D. CRECCA.
